(57) **CLAIM**

The ornamental design for a tail fin for surfboards as shown and described.

DESCRIPTION

FIG. 1 is a perspective view of a tail fin for surfboards showing our new design;

FIG. 2 is a another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the tail fin for surfboards in use.

The broken lines illustrate portions of the tail fin for surfboards which form no part of the claimed design.
